(57) **CLAIM**

The ornamental design for a tool handle, as shown and described.

DESCRIPTION

FIG. 1 is a perspective view of a first embodiment of a tool handle according to the present invention;

FIG. 2 is a plan view of the bottom side of the tool handle of FIG. 1;

FIG. 3 is an elevational view of the front side of the tool handle of FIG. 1;

FIG. 4 is an elevational view of the rear side of the tool handle of FIG. 1;

FIG. 5 is an elevational view of the right side of the tool handle of FIG. 1;

FIG. 6 is a plan view of the top side of the tool handle of FIG. 1;

FIG. 7 is an elevational view of the left side of the tool handle of FIG. 1;

FIG. 8 is a perspective view of a second embodiment of the tool handle according to the present invention;

FIG. 9 is a plan view of the top side of the tool handle of FIG. 8;

FIG. 10 is an elevational view of the right side of the tool handle of FIG. 8;

FIG. 11 is a plan view of the bottom side of the tool handle of FIG. 8;

FIG. 12 is an elevational view of the left side of the tool handle of FIG. 8;

FIG. 13 is an elevational view of the rear side of the tool handle of FIG. 8; and,

FIG. 14 is an elevational view of the front side of the tool handle of FIG. 8.

The broken lines shown herein are for illustrative purposes only and form no part of the claimed design.
